UNITED STATES PATENT OFFICE.

EUGENE PEARL, OF NEW YORK, N. Y.

DESIGN FOR A NIPPLE.

SPECIFICATION forming part of Design No. 31,232, dated July 18, 1899.

Application filed June 9, 1899. Serial No. 719,975. Term of patent 14 years.

To all whom it may concern:

Be it known that I, EUGENE PEARL, a citizen of the United States, residing at New York, in the county and State of New York, have invented and produced a new and original Design for Nipples, of which the following is a specification, reference being had to the accompanying sheet of drawings, forming part thereof, in which—

10 Figure 1 is a view in elevation of a nipple constructed in accordance with my design, and Fig. 2 is a view in plan of the same.

As indicated in the drawings, the nipple 1 comprises a mouthpiece 2 and a body portion 4.

15 The essential or leading feature of my de-

sign consists of an alternating series of ribs and grooves 3, &c., forming surface corrugations upon the upper portion or mouthpiece of the nipple as viewed in Fig. 1, the 20 said corrugations extending entirely around or encircling the same as viewed in Fig. 2.

Having described my invention, what I claim as new is—

The design for a nipple, as herein shown 25 and described.

In testimony whereof I affix my signature in the presence of two witnesses.

EUGENE PEARL.

Witnesses:

BLANCHE S. BELTMAN,

CHARLES A. RYDER.
